(57) CLAIM

The ornamental design for sandals, as shown and described.

DESCRIPTION

FIG. 1 is a perspective view of a right footed sandal of sandals, showing my new design; the left footed sandal is a mirror image of the right footed sandal shown herein;

FIG. 2 is the left side view thereof;

FIG. 3 is a right side view thereof;

FIG. 4 is the front view thereof;

FIG. 5 is a rear view thereof;

FIG. 6 is the top view thereof; and,

FIG. 7 is a bottom view thereof.

The broken lines in the drawings represent unclaimed subject matter and form no part of the claim.
